(74) *Attorney, Agent, or Firm* — ArentFox Schiff LLP

(57) **CLAIM**

The ornamental design for a security tag detacher, as shown and described.

DESCRIPTION

FIG. 1 is a perspective view taken from the top, front and left sides showing the new design;

FIG. 2 is a perspective view taken from the top, front and right sides of the design shown in FIG. 1;

FIG. 3 is a perspective view taken from the top, rear and right sides of the design shown in FIG. 1;

FIG. 4 is a top plan view of the design shown in FIG. 1;

FIG. 5 is a right side view of the design shown in FIG. 1; and,

FIG. 6 is a left side view thereof.

The broken lines shown in the figures are included for the purpose of illustrating portions of the security tag detacher and form no part of the claimed design.

1 Claim, 3 Drawing Sheets
